Fig. 1

Fig. 2

*Fig. 3**Fig. 4**Fig. 5*FIGURE 1 is a front perspective view showing the top and front and one side of a milk carton, showing my new design;

FIGURE 2 is a rear perspective view showing the back, bottom and same side thereof;

FIGURE 3 is a front perspective view showing the top front and one side of the carton of FIGURE 1 in its opened condition;

FIGURE 4 is a rear perspective view of the opened carton showing the back, bottom and same side thereof;

FIGURE 5 is a side elevational view of the opened carton taken on a reduced scale.

The side not shown is the same as the side shown.

My design is characterized by a substantially flat and relatively narrow horizontal top surface merging along its opposite long sides with downwardly diverging rectangular panels that unite at their lower ends with vertical rectangular side panels, each end of the narrow top surface overlying an isosceles trapezoidal recess as shown.

I claim:

The ornamental design for a milk carton or the like, substantially as shown and described.
